DIESTERS OF UNSATURATED GLYCOLS AND
PROCESSES OF PREPARING THE SAME

Anderson W. Ralston and William M. Selby, Chicago, Ill., assignors to Armour and Company, Chicago, Ill., a corporation of Illinois

No Drawing. Application November 22, 1937,
Serial No. 175,978

8 Claims. (Cl. 269—410)

This invention relates to diesters of unsaturated glycols and processes of preparing the same, and it comprises as new materials substances having the general formula

10 wherein R is an alkyl group having from eleven to seventeen carbon atoms, and it further comprises processes wherein fatty acid chlorides corresponding to fatty acids having from twelve to eighteen carbon atoms are reacted with an alkali metal, such as sodium or potassium, for the preparation of such esters.

The fatty acid chlorides, namely those materials having the structural formula RCOCl can be prepared from fatty acids by the action of 20 thionyl chloride, phosphorous trichloride, or phosphorous pentachloride. The fatty acids themselves are extremely abundant and relatively inexpensive, and because of the ease with which these acids can be converted to acid chloride, and 25 the reactivity of the acid chlorides, the fatty acids are important starting materials for the preparation of many organic compounds. The fatty acid chlorides are extremely reactive with alcohols to form esters, and are important reagents in the preparation of materials by a Friedel-Crafts synthesis.

We have now discovered that the fatty acid chlorides having from twelve to eighteen carbon atoms react smoothly with alkali metals, such as 35 sodium or potassium, to give diesters of unsaturated glycols. The reaction is probably as follows:

When the starting chloride is one containing 45 twelve to eighteen carbon atoms the diesters obtained are wax-like materials useful in a number of fields, for example, as dielectrics and in waxing and polishing compositions.

Broadly speaking then, our invention comprises reacting fatty acid chlorides having from 50 twelve to eighteen carbon atoms with alkali metals, namely sodium or potassium, under conditions, as hereinafter specified, leading to the formation of diesters of unsaturated glycols.

55 As starting materials we can use substantially

pure fatty acid chlorides having twelve or more carbon atoms, or we can use mixtures of fatty acid chlorides. For example, we can start with lauryl chloride and obtain as a final product the dilaurate of tetracosene-12,diol-12,13. Or we can start with mixtures of different fatty acid chlorides and obtain mixed esters of the character specified. Consequently, in the appended claims we define our materials by reference to their structural formula and denote the alkyl groups of said formula as having from eleven to seventeen carbon atoms.

We shall now give examples of how our invention may be practised.

Example 1

13.8 grams of sodium ribbon and 500 cc. of anhydrous ether or other inert solvent are placed in a three-necked flask equipped with a motor stirrer, reflux condenser and dropping funnel. 20 109 grams of lauryl chloride, prepared by the action of thionyl chloride and lauric acid, are dissolved in 100 cc. of anhydrous ether or other inert solvent. This solution is then added dropwise to the flask containing the ether and sodium over a period of three and one-half hours. A vigorous reaction takes place which is easily controlled by the rate of addition of the lauryl chloride solution. After the addition of the lauryl chloride the reaction mixture is refluxed for about 25 two hours. The mixture is then filtered from the sodium chloride and excess sodium and the ether removed by distillation, the last traces being removed under an absolute pressure of 20 mm. of mercury. The product is a light-colored, 30 waxy solid. After recrystallization from an acetone-benzene mixture or other solvent, 80.5 grams of product are obtained. On further recrystallization to a constant melting point from acetone-benzene 62.5 grams of final product are 35 obtained having a melting point of 42–3° C. The product is the dilaurate of tetracosene-12,diol-12,13. The proof of the composition of this compound follows:

	Found	Calc.
Saponification number.....	158	153
Iodine number.....	36.4	34.7
Analysis:		
Carbon.....	78.87	78.63
Hydrogen.....	12.63	12.64

In order to further prove the structure of this compound we can saponify it with alcoholic KOH to lauroin and lauric acid. The lauroin obtained 55

has a melting point of 62-3.5° C. These results show that the diester we obtain is:

5

Example 2

- 10 123 grams myristyl chloride are dissolved in 150 cc. of anhydrous ethyl ether and the solution added to 13.8 grams sodium suspended in 500 cc. of ether over two and one-half hours after which the reaction mixture is refluxed for five hours.
- 15 The reaction product is then treated as described under Example 1. After four crystallizations from benzeneacetone 63.5 grams of the dimyristate of octacosene-14,diol-14,15 are obtained having a melting point of 54-55° C. and saponification number of 138. Saponification with 20 alcoholic KOH gives myristoin, melting point 70-71° C.

Example 3

- 25 61 grams of stearyl chloride are dissolved in 75 cc. of anhydrous ethyl ether and the solution added to 6.7 grams of sodium wire suspended in 200 cc. of anhydrous ethyl ether over one hour, after which the reaction mixture is refluxed twenty-one hours. The product is then treated 30 as described under Example 1. After eight crystallization 31 grams of the distearate of hexatriacontene-18,diol-18,19 are obtained having a melting point of 67-68° C. and a saponification num-

ber of 109. Saponification with alcoholic KOH gives stearoin, melting point 78-80° C.

Having thus described our invention, what we claim is:

1. A diester having the structural formula

5

10

wherein the R groups are alkyl radicals having eleven to seventeen carbon atoms.

2. The dilaurate of tetracosene-12,diol-12,13.
3. The dimyristate of octacosene-14,diol-14,15. 15
4. The distearate of hexatriacontene-18,diol-18,19.

5. The process of preparing diesters of unsaturated glycols which comprises reacting a fatty acid chloride having twelve to eighteen carbon atoms with an alkali metal while in an inert solvent for the fatty acid chloride. 20

6. The process of preparing diesters of unsaturated glycols which comprises reacting an ether solution of a fatty acid chloride having twelve to eighteen carbon atoms with an alkali metal. 25

7. The process as in claim 5 wherein the metal is sodium.

8. The process as in claim 6 wherein the metal is sodium. 30
